UNITED STATES PATENT OFFICE.

AMBROSE L. MOORE, SR., OF NEW ORLEANS, LOUISIANA.

RIVET HOLDING AND TRANSPORTING DEVICE.

1,331,718.

Specification of Letters Patent. Patented Feb. 24, 1920.

Application filed April 23, 1919. Serial No. 292,114.

To all whom it may concern:

Be it known that I, AMBROSE L. MOORE, Sr., a citizen of the United States, and a resident of New Orleans, in the parish of Orleans and State of Louisiana, have invented a new and useful Improvement in Rivet Holding and Transporting Devices, of which the following is a specification.

My present invention relates generally to the distribution of heated rivets in connection with structural steel operations where, according to the present practice, it is necessary to have many small forges at various points at or near the points of use. This practice promotes many inconveniences, particularly in connection with bridge building, and the main object of my invention is the provision of simple effective means whereby rivets in a heated state may be distributed from a central heating point and transported considerable distances in the course of such distribution, without losing their heat and without danger to nearby workmen.

The particular means I preferably employ for the above purpose will now be described with reference to the accompanying drawings, forming a part of this specification, and in which—

Figure 1 is a vertical section through my improved device;

Fig. 2 is a similar view taken at right angles to Fig. 1;

Fig. 3 is a side elevation, the carriage being removed, and

Figs. 4, 5, and 6 are horizontal sections taken respectively on lines 4—4, 5—5, and 6—6 of Fig. 1.

Referring now to these figures, my invention proposes a rivet carrier, the body 10 of which has inner and outer walls 11 and 12, the body 10 being vertically cylindrical and the walls 11 and 12 being spaced apart to provide for necessary insulation of the inner chamber within the inner wall 11.

An intermediate wall 13 is also preferably employed in spaced relation around the inner wall 11 to form an annular vacuum chamber 14 therebetween, and still have an annular space between the said intermediate wall 13 and the outer wall 12 for the reception of suitable insulating material 15.

The top 16 of the body is cut away above the upper open end of the inner or central chamber and has guides for a laterally sliding cover 17 provided with an outer handle

18, and this top 16 also has at diametrically opposed points a pair of upstanding lugs or brackets 19.

To the lugs or brackets 19 there may be attached a handle, or, as shown in Figs. 1 and 2, the depending bail 20 of a carriage 21 having wheels 22 for movement on a guiding cable 23 or any suitable overhead track.

The base 24 of the body is similarly cut away below the lower open end of the inner or central chamber and has guides for upper and lower discharge plates 25 and 26 having non-aligned openings, and a discharge slide 27 having an opening shiftable from a point opposite the opening of plate 25 to the opening of plate 26 and vice versa. The plate 25 in its normal position has its opening aligned with the axis of the inner chamber and with the opening of the discharge slide 27 when the latter is in its inner position. The discharge slide 27 is moreover of a thickness at least equal to the length of a rivet so as to accommodate a rivet and shift the same into discharge position by virtue of alinement with the discharge plate opening. These plates 25 and 26 have outer handles 28 and 29 and the discharge slide 27 has an outer handle 30.

The inner chamber within the inner wall 11 receives a cylindrical, axially bored rivet container 31 formed of metal or some suitable heat-receiving material so that it may, if desired, be heated along with a supply of rivets 32 disposed in end to end relation within its bore. After being so heated the container is slipped into the inner chamber, and with the upper discharge plate 25 partially removed it is obvious the lower end of the bore will be closed. Likewise, with the cover 18 in effective position the upper end of the bore is closed so that with the vacuum space 14 and the surrounding insulation, it is obvious the holder may be transported for a considerable distance without danger of undesirable cooling of the rivets.

When the holder has been transported to the place of use, the upper discharge plate 25 is then shifted inwardly so that the lowermost rivet can drop into the opening of the discharge slide 27. Outward movement of this discharge slide then serves to permit this rivet to drop out through the opening of the discharge plate 26.

If so desired, the lower end of the container 31 may have guides 33 for a bottom

closure (not shown) for use therewith while heating the container and its supply of rivets, the latter of which may be separated by small disks of asbestos or like material to prevent sticking.

I claim:—

- 5 1. A rivet holder having a body or casing provided with an inner insulated chamber, a removable closure above said chamber, a rivet container movable into and out of the chamber, and a discharge member normally closing the lower end of the chamber.
- 10 2. A rivet holder having a body or casing provided with an insulated chamber, a discharge slide having a rivet receiving aperture and normally closing the lower end of said chamber, a removable closure for the upper end of the chamber, and a tubular rivet holder removably disposed in said chamber.
- 15 3. A rivet holder having a body or casing provided with an inner rivet chamber, means normally closing the upper end of said chamber, and means normally closing

the lower end of the chamber and including 25 a member movable to individually discharge the rivets from the chamber.

4. A rivet holder having a body or casing provided with an inner insulated chamber for the rivets, a top closure, and a base having 30 discharge plates provided with non-alined openings and a discharge slide movable between said plates and having a rivet receiving opening shiftable into alinement with the opening of each of said plates. 35

5. A rivet holder having a body or casing provided with an inner insulated chamber, a removable closure above said chamber, a rivet container movable into and out of the chamber, and a base normally closing the 40 lower end of the chamber and including discharge plates provided with non-alined discharge openings, and a discharge slide movable between said plates and having a rivet receiving opening shiftable into alinement 45 with the discharge opening of each of said plates.

AMBROSE L. MOORE, SR.
